BROOM OR ARTICLE OF ANALOGOUS NATURE

Alfred L. Lodge, Boston, Mass., assignor of one-half to Carl L. Braun, Lowell, Mass.

Application July 29, 1935, Serial No. 33,737

12 Claims. (Cl. 15—159)

The present invention relates to brooms and articles of analogous nature. More particularly, the present invention relates to such articles provided with a handle detachable from the sweeping or brushing portion thereof.

As now on the market, household brooms are what may be called one-piece articles, meaning by that that the broom head is fixed permanently on the handle, and the two parts are bought, sold, and used as a unit. While so far as use is concerned this unitary construction is convenient, there are advantages in having a broom which is unitary in use but which can upon occasion be disassembled into a sweeping unit and a handle. One advantage lies in manufacture, inasmuch as the labor of uniting the handle with the broom corn and of forming the shoulders at the top of the broom head is eliminated. Another advantage lies in shipping the disassembled parts from the factory and in storing them in places where they are sold. Bundles of ordinary brooms, because of their length and irregular shape, are bulky and occupy a space out of proportion to their actual size both for the shipper and for the retail merchant. Broom head units and handles detached therefrom are more conveniently stored. A further advantage lies in the fact that when a broom head unit wears out, it is more economical to purchase and more convenient to carry merely a replaceable broom head unit than it is a complete broom.

It is the principal object of the present invention to provide what may be called a two-piece broom, meaning by that a broom comprising a broom head unit provided with a readily removable handle.

It is a further object of the present invention to provide a broom head unit which is strong in construction so that the broom corn or sweeping elements of some other material will not pull or fall out, which is cheap to manufacture, and which may be readily removed from a handle so that a new broom head unit may be substituted therefor and held securely in place.

In the present manufacture of ordinary brooms, the ends of a quantity of broom corn are bound with wire around an end portion of the handle, whereupon the corn is bent from its point of attachment to the handle and flattened to form the curved shoulders at the top of the broom head. Below the shoulders the corn is stitched so that the broom head will retain its shape. The shoulders of ordinary broom heads constitute points of weakness, in that the portions of the corn composing them are distorted, are always

under strain, and always tend to pull away. In use it not infrequently happens that these shoulders break, rendering the broom useless before the sweeping portion is worn out.

It is therefore a further object of the present invention to provide a broom in which this shoulder weakness is eliminated.

To the accomplishment of these objects and such others as may hereinafter appear, the various features of the present invention reside in certain combinations, devices, and arrangements of parts fully described hereinafter and then pointed out in the appended claims, possessing advantages which will be readily apparent to those skilled in the art.

The various features of the present invention will be readily understood from an inspection of the accompanying drawings illustrating the best form of the invention at present known to the inventor, in which,

Figure 1 is a view in front elevation of a broom made according to my invention;

Fig. 2 is a disassembled view in front elevation of the broom shown in Fig. 1;

Fig. 3 is a view in perspective of the base member of the clamp;

Fig. 4, is disassembled relation to Fig. 3, is a view in perspective of the binding member of the clamp;

Fig. 5 is a sectional view taken along the line 5—5 of Fig. 1;

Fig. 6 is a detail view in sectional elevation of the handle, the cover, and the clamp for securing the broom head unit to the handle; and

Fig. 7 is a sectional view taken along the line 7—7 of Fig. 5.

Referring to the accompanying drawings, the illustrated embodiment of the present invention is provided with a clamp comprising metallic telescoping members 10 and 11, respectively, best shown in Figs. 3 and 4, which function to bind end portions of a quantity of sweeping elements 12 such as broom corn together into a broom head unit. For convenience in disclosure, the member 10 will be called hereinafter a base member and the element 11 a binding member.

Referring to Fig. 3, the base member 10 comprises a side wall 13, parallel bent ends 14 from which lugs 15 extend so as to form shoulders 16, and lugs 17 bent into parallelism with the ends 14 and the lugs 15. The lugs 17 are preferably as long as the combined lengths of the bent ends 14 and the end lugs 15. The base member 10 is formed from a single blank, the lugs 17 being struck from the wall 13 and then bent away

from the ends 14 so as to leave wall openings 18. The wall 13 is also provided with a central opening 19.

Referring to Fig. 4, the binding member 11 comprises a side wall 20 having the same width as the wall 13 and provided with parallel bent ends 21. The binding member 11 is adapted to telescope over the base member 10, and to this end, the binding member is provided with end 10 slots 22 for receiving the end lugs 15 of the base member and with slots 23, wider than the slots 22, for receiving the lugs 17. The wall 20 is also provided with a central opening 24. When the base and binding members are telescoped together completely, the shoulders 16 engage the wall 20 of the binding member and so limit the approach of the base and binding members toward each other, and the central openings 19 and 24 are aligned.

In assembling the base and binding members together with a quantity of sweeping elements such as the broom corn 12 so as to form a broom head unit, the base member 10 is placed in a suitable support and end portions of a quantity 25 of the corn are placed in it to a level above that of the shoulders 16 and in engagement with the wall 13, the bent ends 14, and the lugs 15 and 17. Thereupon the binding member 11 is telescoped over the base member 10 and is pressed 30 with considerable force against the corn 12 so as to compress it preferably to such an extent that the wall 20 of the binding member 11 engages the shoulders 16. As a result, the individual pieces of corn are compressed together in successive juxtaposition from the wall 20 through 35 to the wall 13.

While the base and binding members are held telescoped under pressure, the end lugs 15 which extend through the slots 22 are bent into engagement with the binding member wall 20, as shown in Fig. 5, and the lugs 17 which project through the slots 23 are bent towards the lugs 15 and into engagement with the wall 20. The bent ends of the lugs thus serve to hold the base and binding members together in corn-clamping position after the pressing force has been removed, the end lugs 15 holding the members in corn-clamping position at their end portions and the lugs 17 holding the members in corn-clamping position at 50 points spaced from their end portions and so preventing bulging of the members.

In order to lock the bent lugs in pressing position, the end portions of the wall 20 are provided with outwardly struck ears 25 (Fig. 4) arranged 55 in oppositely disposed pairs and adapted to be bent over into engagement with the lugs 15 and 17, as shown in Figs. 2, 5 and 7.

When the corn 12 is placed in the base member 10 as above described, the end portions of the 60 corn may be aligned with an edge of the wall 13. It is preferred, however, that these end portions project slightly beyond the edge, whereupon the corn is trimmed to the level of the edges of the walls 13 and 20, as shown in Fig. 7, after the base 65 and binding members have been secured together.

The structure so far described is shown clearly in Fig. 5. For reasons which will be given hereinafter, the space between the bases of the lugs 17 is such that before the lugs are bent they engage the inner walls of the slots 23. As will be 70 seen in Fig. 5, after the lugs 17 are bent into engagement with the binding member 11, the lugs are spaced from the inner walls of the slots 23 and engage the outer walls thereof. This causes 75 the portion of lugs 17 which lie between the base

and binding members to slant outward to a slight degree, the amount of slant being exaggerated in the drawings and in reality being of no greater extent than the thickness of the material, as will be explained.

The structure so far described comprises a broom head or sweeping unit made up of the telescoped base and binding members 10 and 11 which are held in a condition to clamp the broom corn 12 securely together. The corn extends 10 downwardly beneath the telescoped members to present the appearance, except at the top, of an ordinary broom head. Beneath the telescoped members the corn is provided with the usual stitching 26.

In making a broom head unit such as above described, it would be practical to a certain extent to leave the side walls 13 and 20 as they have been so far described. Enough pressure could be applied in forming the unit so that under ordinary usage the corn would not easily pull out. But the disadvantage of such a construction lies in the fact that the individual lengths of corn would all be substantially parallel and would be held together by smooth surfaces which would by no means give the frictional grip that roughened surfaces would give. While there would be a tendency for the corn exposed by the openings 18 to bulge out slightly into the openings, this bulging would occur in so small a quantity of the corn as to be of no great benefit in helping to maintain the entire body of the corn in place. Accordingly, the present invention contemplates the provision of auxiliary corn-compressing means so that certain local areas of the clamped corn are distorted and subjected to greater clamping pressure than others.

Referring to Fig. 3, the side wall 13 is provided adjacent its top and bottom edges with inwardly directed ridges 27 extending substantially the length of the wall. The portion of the wall between the lugs 17 is provided with a pair of ridges 28 one on each side of the central opening 19. Referring to Fig. 4, the wall 20 is provided with inwardly directed ridges 29 and 30 corresponding to the ridges 27 and 28, respectively, and between the oppositely disposed ears 25 the end portions of the wall 20 are each provided with an inwardly directed ridge 31. All these ridges extend lengthwise of their respective walls and therefore crosswise of the clamped corn. With this construction the ridges compress the corn to a greater extent than do the flat portions of the walls 13 and 20. Stated in another way, the ridges 21, 28, 29, 30, and 31 subject local areas of the corn to an increased pressure over the pressure to which the flat portions of the walls 13 and 20 subject it. The compressing effect of the ridges 27, 29 and 31 is indicated in Fig. 7, from which it will be seen that the portions of the corn adjacent the walls 13 and 20, instead of being straight, are bent inwardly at a plurality of places. The increased localized pressure applied by the ridges 28 and 30 is applied in a manner identical with that of the ridges 27, 29, and 31. Since the 65 ridges are formed on the walls 13 and 20, it will be seen that the increased localized pressure resulting from the ridges comes from the exterior of the clamped corn, and serves to clamp the corn more securely in place.

In addition to subjecting portions of the clamped corn to an increased localized pressure from without, the present invention contemplates the provision for such pressure from within. To achieve this the bent ends 21 of the binding mem-

ber 11 are each provided with an opening 32 (Figs. 4 and 5) and the bent ends 14 of the base member 10 are each provided with a preferably elongated opening 33 adapted to register with an opening 32 when the two members are telescoped together. The lugs 17 are also each provided with an opening 34 larger than the openings 32 and in registry with the elongated openings 33. After the base and binding members are clamped in position about the corn 12, and the lugs 15 and 17 and the ears 25 are bent down as described above, headed pins 35 (Fig. 5) are driven one at each end through the registering openings 32 and 33, then crosswise through the corn 12, then through the enlarged openings 34 in the lugs 17, each pin terminating short of an opening 36 drilled in the corn in registry with the aligned openings 19 and 24. By making the openings 34 larger than the openings 32, the pins 35 will pass into the openings 34 notwithstanding slight deviations from the intended path of the pins as they are driven. The heads of the pins 35 serve to hold the bent ends 14 and 21 together.

Viewing Figs. 5 and 7, it will be seen that the pins 35 perform the same corn bending function as is performed by the ridges 27, 28, 29, 30, and 31, but that in the case of the pins, the pressure is exerted from within outwardly. Stated in another way, the pins 35 provide an increased localized pressure against portions of the clamped corn, this pressure being exerted from within the corn outwardly in the direction of the base member 10 and the binding member 11, including the openings 18 in the former.

The broom head unit above described is intended to be detachably secured to an ordinary broom handle. To this end the lower end of a handle 37 is provided with a two-piece clamp comprising curved portions 38 and 39 (Figs. 2 and 6) adapted to embrace the end of the handle 37 and be held there by a male and female screw unit 40. The opposite ends of the screw unit 40 extend slightly outside the curved portions 38 and 39 for a purpose presently to be described.

The lower ends of the curved portions 38 and 39 broaden out into square jaws 41 and 42, respectively, (Figs. 2 and 6). The sides and bottom of each jaw are curved inwardly to form rounded strengthening lips 43 and 44. Each jaw is adapted to fit over the central portion of the broom head unit, with the edges of the lips 43 and 44 engaged with the walls 13 and 20 of the base and binding members, respectively.

Referring to Figs. 5 and 6, it will be seen that each side of the curved lip 43 of the jaw 41 is provided with a lug 45 and that each side of the curved lip 44 of the jaw 42 is provided with a lug 46. These lugs have a length substantially equal to the width of the openings 18 in the base member 10. It was pointed out above that the slots 23 of the binding member 11 were wider than the slots 22 thereof, and that when the lugs 17 are bent into engagement with the wall 20 the lugs are spaced from the inner walls of the slots 23 as shown in Fig. 5. Specifically, the slots 23 are just wide enough to receive both the lugs 17 and the lugs 45 of the jaw 41. With this construction, the edges of the jaw lips 43 engage the wall 20 of the binding member 11 and the jaw lugs 45 engage the inner walls of the slots 23 and the lugs 17, extending a short way into the corn 12, as shown in Fig. 5. As a consequence, when the jaw 41 is secured to the broom head unit, as will be described, the jaw, and therefore the attached

handle end, cannot shift angularly of the broom head in the direction of the length of the telescoped members 10 and 11.

The lugs 46 on the jaw 42 perform the same function as the lug 45, and extend slightly into the straw through the openings 18 with the edges of the jaw lips 44 engaged with the wall of the base member 10. Since it is desirable, as a commercial matter, that the jaws 41 and 42 be stamped from the same die, it is necessary to bend the lugs 46 of the jaw 42 slightly outwardly, as shown in Fig. 5. In this manner the lugs 46 hug the lugs 17 tightly at their base and since the lugs 46 extend into the openings 18, they function to prevent movement of the jaw 42 angularly of the broom head in the direction of the length of the telescoped members 10 and 11.

The jaws 41 and 42 are provided with oppositely disposed openings 47 and 48 which, when the jaws are positioned properly on the broom head unit, are adapted to register with the passage comprising the opening 24 in the binding member 11, the opening 19 in the base member 10, and the opening 36 formed in the corn 12. The jaws and the broom head unit are detachably connected together by preferably a male and female screw unit 49 (Fig. 1) which extends through the above named passage. When the screw units 40 and 49 are both tightened, the lugs 45 and 46 are forced into the slots 23 and around the bases of the lugs 17, respectively, until the edge of the curved lips 43 and 44 engage the binding and base members, respectively, thereby distributing the gripping pressure of the jaws 41 and 42 over a larger area than would be the case were the jaws entirely flat and providing for a rigid junction between the handle 37 and the broom head unit.

In order to conceal the clamped end portion of the corn 12 and the handle attaching means and to protect furniture and other objects which the metallic parts might strike when the broom is used, the present invention contemplates the provision of a cover 50 of molded rubber, composition, papier-mâché, or any other suitable material, rubber being preferred because of its resiliency. As indicated in Figs. 1, 2 and 6, the cover 50 comprises a neck portion 51 and a body portion 52 adapted to fit snugly over the upper end of the clamped corn and extend down to a point adjacent the stitches 26 and below the base member 10 and the binding member 11. The neck portion 51 is adapted to embrace and conceal the curved portions 38 and 39 of the handle clamp and may be provided with oppositely disposed openings 53 into which the opposite ends of the male and female screw unit 40 extend. This construction, by reason of the resiliency of the neck 51, provides that the openings 53 comprise in effect shoulders against which the ends of the screw unit 40 abut to hold the cover removably in place. It will be apparent, however, that other types of cover securing means may be employed, and that the cover may even be held in place by the snug fit of resilient materials.

Several advantages will be seen in the above-described construction. By forming the broom head unit independently of the handle, there is eliminated the labor required in making ordinary brooms in securing the corn to the handle and then distorting and bending it to form shoulders extending from the point of attachment with the handle. By the elimination of such shoulders, none of the shoulder strain and weakness characteristic thereof is found in the illustrated em-

bodiment of the present invention. From a manufacturing point of view, the materials comprising the broom head unit disclosed are cheap and may be assembled without difficulty. When it is 5 desired to replace a broom head unit with a new one, the cover 49 may be slipped up the handle 37 as shown in Fig. 2, the screw units 48 and 49 loosened, and the broom unit slipped out from between the jaws 41 and 42. Then a new unit may be 10 easily secured to the handle 37 by causing the jaws 41 and 42 to fit over the broom head unit properly, whereupon the screw units 48 and 49 are tightened to force the lugs 45 and 46 into the slots 23 and around the bases of the lugs 17, respectively, and to cause the jaw lips 43 and 44 to embrace the broom head unit securely. The cover 50 is then pulled down to conceal the top of the unit, the ends of the screw unit 48 entering the openings 53 in the neck of the cover to maintain 20 it in place. The broom head unit is self-contained, in that the corn is clamped in place independently of the handle attaching means, thereby providing that units may be substituted without disturbing the clamping condition of the base and 25 binding members.

The present invention has been described as embodied in a broom for ordinary household purposes, employing the usual broom corn. It will be apparent, however, that the present invention 30 is broader than this, being adapted to other types of brooms and articles of analogous nature, and that as sweeping elements other materials such as bristles or limp strands may be employed in place of broom corn. The structure chosen for 35 purposes of disclosure is well suited to one form of the invention, but it is to be understood that its scope is not limited to the details of the structure shown nor to the conjoint use of all its features, for they may be variously modified within 40 the skill of the artisan without departing from the true scope of the present invention, characterizing features of which are pointed out in the appended claims by the intentional use of generic terms and expressions inclusive of various modifications.

45 What is claimed as new is:

1. In a broom or article of analogous nature, the combination with a quantity of sweeping elements and clamping means having ends and side 50 walls surrounding an end portion of the elements to bind them securely together, of means extending through the clamp ends and also extending substantially throughout the length of the clamp in engagement with said bound end portions for 55 holding the clamp ends together and for urging the bound elements from within outwardly against said side walls substantially throughout their length.

2. A head for a broom or article of analogous 60 nature comprising, in combination, a quantity of sweeping elements, telescoping members adapted to receive end portions of the sweeping elements to clamp them together in successive juxtaposition, means for holding the members telescoped 65 together in clamping position, and means engaged with some of said clamped end portions and extending substantially throughout the length of the clamp for urging said clamped end portions from within outwardly against said telescoped members.

70 3. A head for a broom or article of analogous nature comprising, in combination, a base member holding a quantity of sweeping elements and provided with lugs, a binding member engaging 75 the sweeping elements and provided with lug-

receiving slots, the lugs extending through the slots and being bent into engagement with the binding member to hold it pressed against the sweeping elements so that they are clamped between the two members, and means carried by 5 the binding member for locking the bent lugs in pressing position.

4. A head for a broom or article of analogous nature comprising, in combination, a base member holding a quantity of sweeping elements and 10 provided with ends, a side wall, and lugs, a binding member engaging the sweeping elements and provided with ends, a side wall, and lug-receiving slots, the lugs extending through the slots and being bent into engagement with the side wall of 15 the binding member to hold it pressed against the sweeping elements so that they are clamped between the two members, and means for applying increased localized pressure against the clamped elements from the exterior thereof. 20

5. A head for a broom or article of analogous nature comprising, in combination, a base member holding a quantity of sweeping elements and 25 provided with ends, a side wall, and lugs, a binding member engaging the sweeping elements and provided with ends, a side wall, and lug-receiving slots, the lugs extending through the slots and being bent into engagement with the side wall of said binding member to hold it pressed against the sweeping elements so that they are clamped 30 between the two members, means for applying increased localized pressure against the clamped elements from the exterior thereof, and means for applying increased localized pressure from within the clamped elements outwardly in the direction 35 of the base and binding members.

6. A head for a broom or article of analogous nature comprising, in combination, a base member holding a quantity of sweeping elements and 40 provided with bent ends and lugs, a binding member engaging the sweeping elements and provided with lug-receiving slots and with bent ends adapted to fit over the bent ends, respectively, of the base member, the lugs extending through the slots and being bent into engagement with said binding member to hold it pressed against the sweeping elements so that they are clamped between 45 the two members, and means for securing the ends of the base and binding members together, respectively, and for urging the clamped elements 50 outwardly against said members.

7. A head for a broom or article of analogous nature comprising, in combination, a base member holding a quantity of sweeping elements and 55 provided with ends, a side wall, and lugs, a binding member engaging the sweeping elements and provided with ends, a side wall, and lug-receiving slots, the lugs extending through the slots and being bent into engagement with the side wall of the binding member to hold it pressed against 60 the elements so that they are clamped between the two members, and means for limiting the approach of the binding member towards the base member upon the reception of the lugs by the slots.

8. In a broom or article of analogous nature, the combination with a handle, a sweeping unit comprising a quantity of sweeping elements and a clamp securely binding the elements together, means for connecting the handle to the sweeping unit, and a cover for concealing the connecting means and the adjacent portion of the sweeping unit, of means carried by the cover cooperating 70 with the connecting means for removably maintaining the cover in concealing position. 75

9. In a broom or article of analogous nature, the combination with a handle, a sweeping unit, means for connecting the handle to the sweeping unit, and a cover comprising a neck and a body portion for concealing the connecting means and the adjacent portion of the sweeping unit, of means carried by the neck in engagement with the connecting means and cooperating therewith for removably maintaining the cover in concealing position.
10. In a broom or article of analogous nature, the combination with a handle, a broom head unit comprising a clamp and a quantity of sweeping elements securely bound thereby, and clamp-
- 15 gripping means including a portion extending interiorly of the unit for detachably securing the handle to the unit, of means forming part of the securing means separate from the portion thereof extending interiorly of the unit and cooperat-
- 20 ing with the clamp for preventing angular movement of the securing means in the direction of the length of the clamp.
11. In a broom or article of analogous nature, the combination with a handle, a broom head unit
- 25 comprising a quantity of sweeping elements and a clamp securely binding the elements together,
- said clamp being provided on its opposite sides with openings, and means for gripping the sides of the clamp to detachably secure an end of the handle to the broom head unit in such position that said handle end is exterior to the bound sweeping elements, of means forming part of the securing means and cooperating with the openings for preventing angular movement of the securing means in the direction of the length of the clamp.
12. A head for a broom or article of analogous nature having, in combination, a base member holding a quantity of sweeping elements and provided with ends, a side wall, and lugs, a binding member engaging the sweeping elements and provided with ends, a side wall, and lug-receiving slots, the lugs extending through the slots and being bent into engagement with the side wall of the binding member to hold it pressed against the sweeping elements so that they are clamped between the two members, and means for applying increased localized pressure from within the clamped elements outwardly in the direction of the walls of the base and binding members.

ALFRED L. LODGE.

25
